VACUUM MUFFLER

Charles L. Hill, Cranford, N. J.

Application August 3, 1940, Serial No. 350,199

4 Claims. (Cl. 181—56)

This invention relates to improvements in engine mufflers, and has particular reference to a vacuum muffler of the type shown and described in U. S. Letters Patent No. 1,351,698, granted Charles L. Shuman and Soren Scott Hanson under date of August 31, 1920.

One of the important features of the invention resides in a vacuum muffler especially adapted for heavy duty engines such as are used on heavy duty motor trucks, tractors, busses, marine motors, stationary engines and any other type of combustion power plant.

One of the important features of the invention resides in a muffler which eliminates back pressure by utilizing the velocity energy of the hot waste gases of combustion as they pass therethrough.

Another feature of the invention is to provide a vacuum muffler which functions to induce the free passage of waste gases of combustion therethrough, thus reducing back pressure on an engine to an extent below atmospheric pressure, and preventing accumulation of gases within the muffler which may cause an explosion or backfire.

Other features are to provide a vacuum muffler which is simple of construction so as to facilitate the easy taking of the same apart for cleaning and reassembly, and which is strong and durable to withstand the pressure and heat to which the same may be subjected when in use.

Other features of the invention will become apparent as the following specification is read in conjunction with the accompanying drawings, in which:

Figure 1 is a front elevational view of the vacuum muffler.

Figure 2 is an enlarged vertical transverse sectional view on the line 2—2 of Figure 1.

Figure 3 is an inside face elevational view of the front casing section per se.

Figure 4 is an inside face elevation of the rear casing section with the intermediate baffle members in position thereon and illustrating the front face of the forward baffle member.

Figure 5 is a rear face elevational view of the forward baffle member per se.

Figure 6 is a view similar to Figure 4 with the forward baffle member removed and looking at the front face of the rear baffle member.

Figure 7 is a rear face elevational view of the rear baffle member per se.

Figure 8 is an inside elevational view of the rear casing section.

Figure 9 is an enlarged detail vertical transverse sectional view on the line 9—9 of Figure 2.

Referring to the drawings by reference characters, the numeral 10 designates my vacuum muffler in its entirety, which broadly includes a front casing section A, a rear casing section B, a forward intermediate baffle member C and a rear intermediate baffle member D, all of which are formed of cast durable metal capable of 5 withstanding the heat and pressure of the heated waste gases of combustion to which they are subjected during use of the muffler.

The front casing section A is in the form of an annular shell and includes a side wall 11 and an annular peripheral flange 12 having an annular groove 13 in the rear face thereof. Formed integral with the side wall 11 and extending forwardly thereof and axially relative thereto is a collar 14 having an inlet 15. The collar 14 is adapted to be connected to the outlet end of 15 an exhaust pipe leading from the exhaust manifold of an internal gas combustion engine. The side wall adjacent its periphery is provided with four equi-distantly spaced bolt openings 16. 20 Formed integral with and extending rearwardly of the side wall 11 are equi-distantly spaced arcuate baffles 17 which are helically directed toward the inlet 15, the adjacent baffles being in outwardly diverging relation. The ends of the 25 baffles 17 are curved and thereby gradually diminish in width and they terminate short of the flange 12 and inlet 15. Certain adjacent baffles 17 are connected approximately midway of their ends by webs 18, each of which has a notch or 30 seat 19 to receive cooperating baffles provided on the front face of the baffle member C and which will be fully described hereinafter.

The rear casing section B is also in the form of an annular shell and includes a side wall 23 and an annular peripheral flange 24 having an annular rib 22 on the free front face thereof which is complementary to and snugly fits into the groove 13. The open sides of the front and rear casing sections A and B are disposed in confronting relation and enclose the intermediate sections C and D in a manner to be hereinafter more fully explained. Formed integral with and extending rearwardly thereof and axially relative thereto is a collar 23 having an outlet 24. The inlet 15 and outlet 24 are in axial alinement as best illustrated in Figure 2 of the drawings. The side wall 20 adjacent its periphery is provided with four equidistantly spaced bolt openings 25, which are shown as square in cross section to receive the square portions at the head 35

ends of fastening bolts 26. The openings 25 respectively align with the openings 16 so that the bolts 26 may pass therethrough with the threaded shanks thereof extending beyond the casing section A and receiving clamping nuts 27. Formed integral with and extending forwardly from the side wall 20 are two spiral baffles 28-28. Each baffle 28 extends from an edge of the outlet 24 and terminates adjacent but in spaced relation to the flange 21, after making a complete convolution as best seen in Figure 8 of the drawings. The inner ends of the baffles 28-28 extend from diametrically opposite sides of the outlet 24 and their outer ends terminate at substantially diametrically opposite points. The spiral baffles 28-28 are so spaced that two helical passages 29-29 are provided which gradually increase in width from their outer inlet ends which open into the outlet 24. The spiral baffles 28-28 are of a uniform width throughout their length except that they have their outer ends gradually reduced or inclined as at 30. The baffles 28-28 have equi-distantly spaced spacer lugs 31 extending from the free edges thereof for maintaining the baffle member D in spaced relation to the spiral baffles 28-28 of the casing section B.

The baffle member C comprises an annular plate 32 having a concentric opening 33 therein, the walls of the opening being flared forwardly as at 34. The plate 32 is provided with a curved rearwardly extending flange 35 and extending inwardly from the flange are equi-distantly spaced arcuate baffles 36, the inner ends of which terminate short of the opening 33. Adjacent baffles extend in outwardly diverging relation, thus the space therebetween is wider at the outer ends than at the inner ends. Three of the baffles 36 are arranged at one hundred and twenty degrees apart and are wider than the other baffles for abutting engagement with the front sides of the baffle member D, for maintaining the members C and D in a fixed spaced relation. The periphery of the member C is notched as at 37 at four equi-distantly spaced points to receive the shanks of the bolts 26.

The front side of the baffle member C is provided with an annular series of arcuate baffles 38 which have their ends terminating short of the periphery thereof and short of the opening 33 as best seen by reference to Figure 4. Adjacent baffles 38 are disposed in outwardly diverging relation so that the space between the baffles is wider at the outer end than at the inner end. Three of the baffles arranged at one hundred and twenty degrees apart are wider than the others so as to abut the member A to maintain the member C in a fixed spaced relation relative thereto. The baffles 38 are staggered relative to the baffles 17, so as to fit between each other in spaced overlapping relation and provide double the passages between the baffles 17 and 38 to effect an initial separation and cooling of the gases after entering the inlet 15.

The baffle member D comprises an annular plate 39 having a forwardly extending concentric cone portion 40 and a rearwardly extending axial hub portion 41 which terminates adjacent the walls of the outlet 24 to provide an annular restricted passage 50 between the outlet chamber and the outlet. The periphery of the plate 39 is notched at four equi-distantly spaced points as at 42 to receive the shanks of the bolts 26. The front side of the plate 39 is provided with an annular series of arcuate baffles 43 which ter-

minate short of the periphery of the plate and short of the cone 40 (see Figure 6). The adjacent baffles 43 are in spaced outwardly diverging relation and gradually diminish in width from their inner ends to their outer ends. Notched seats 44 are provided on the front face of the plate 39 at one hundred and twenty degrees apart to receive the three relatively wide baffles 36 of the baffle member C. The baffles 43 interfit between and are maintained in spaced relation with respect to the baffles 36 with the apex of the cone portion 40 extending axially into the opening 33. The baffles 43 and 36 coact to double the number of passages between the members C and D and serve to initially break up and cool the heated gases which may enter through the opening 33.

The rear face of the plate 39 is provided with two spiral baffles 45-45 which are similar to and are complementary to the spiral baffles 28-28 of the member B. The inner ends of the baffles 45-45 terminate at the hub 41 at diametrically opposite points while the outer ends thereof terminate in gradually decreasing width short of the periphery of the plate 39 (see Figure 7). The spiral baffles 45 fit into the spaces 20-20 of the baffle member B and spiral baffles 28-28 overlap the spiral baffles 45-45 as best seen in Figure 2. The lugs 31 on the baffles 28 abut the rear face of the plate 39 of the baffle member D to maintain the free edges of the baffles 28 and 45 in a fixed spaced relation. The casing sections A and B, and baffle members C and D coact to provide two gas inlet chambers X and Y and a communicating outlet chamber Z, through which the hot gases must pass from the inlets 15 and 33 to the common outlet 24.

In practice, assume that the collar 14 is connected to the outlet end of an exhaust pipe leading from the exhaust manifold of an internal combustion engine. The inlet 15 is of a greater diameter than the opening 33 in the forwardly flared portion of the baffle member C. The solid stream of gases entering the inlet 15 is broken up into a core stream which enters the inlet chamber Y through the opening 33 and an outer ring stream which enters the inlet chamber X between the baffle member C and front casing section A. Thus the volume of the gases entering the muffler is initially divided, a proportionate amount being lead to the chamber X, and a proportionate amount being lead to the chamber Y. The overlapping arcuate baffles 17 and 38 and the overlapping arcuate baffles 36 and 43 are disposed in the path of the laterally deflected gases and these baffles act to cool the subdivided streams of gases as they flow toward the periphery of the members C and D. By reason of the arcuate shape of the baffles 17-38, 36-43, the cooled gases are lead to the periphery of the members C and D in whirling streams, which cooled gases enter the outlet chamber Z defined by the baffle member D and rear casing section B. This chamber Z is divided into four spiral communicating passages which have their inner ends meeting at the common outlet 24. The baffles 17, 38, 36, and 43, transfer their heat to the casing section 11, plate 32, and plate 39 respectively, and are thus cooled by conduction, for the casing sections and plate radiate the heat to the atmosphere. The initial cooling of the heated gases materially reduces the volume of the gases which enter the space between the spiral baffles 28 and 45 in a whirling state, and the cooled gases are maintained in whirling motion

in a direction toward the annular restricted passage communicating with the outlet 24. As the initially cooled gases pass about the spiral baffles 28 and 45, they are further subjected to cooling action and when reaching the outlet 24, the gases are exhausted to the atmosphere in a substantially noiseless stream. The whirling action of the gases during their travel through the muffler tends to induce the flow of the same, and prolongs the passage of the hot gases to assure cooling and avoids the accumulation of hot gases which are responsible for back pressure and back firing.

By reason of the novel construction of my improved vacuum muffler, it is possible to quickly take the same apart for cleaning when the occasion demands. It is only necessary to remove the nuts 27 from the bolts 26, withdraw the bolts, whereupon the sections A, B, C and D, will readily become separated. The several sections may be cleaned of any accumulation of carbon, and the parts readily reassembled.

Having thus described the invention, what I claim as new and desire to secure by Letters Patent of the United States, is:

1. A vacuum type muffler comprising in combination, an annular casing having an axially aligned inlet and an outlet in the respective opposed end walls thereof, a pair of baffle members, means for maintaining said baffle members in spaced parallel relation from each other and in spaced relation to the walls of said casing to provide a pair of gas inlet chambers and a single gas outlet chamber, the baffle member nearest the inlet having a gas inlet opening in axial alignment with said inlet but of a smaller diameter, spaced overlapping arcuate shape baffles on the confronting side walls of the inlet chambers to cause a whirling of the hot gases as they pass through the inlet chambers and for initially cooling the hot whirling gases, and spaced spiral overlapping baffles provided on the confronting side walls of the outlet chamber, the inner ends of the spiral baffles terminating at said outlet whereby the initially cooled gases are further cooled and whirled as they pass about the spiral baffles to be exhausted to the atmosphere through said outlet.

2. A vacuum type muffler comprising in combination, a two part circular casing, one of said parts having a central gas inlet and a series of arcuate baffles on its inner surfaces, the other of said parts having a central outlet and a series of spiral baffles on the inner side thereof surrounding said outlet, a pair of spaced plates, means for mounting said spaced plates in spaced relation to the walls of said casing, the plate nearest said inlet having a concentric inlet opening of smaller diameter than said inlet, the other of said plates having a stream diverting

cone extending toward said inlet opening, spaced overlapping arcuate baffles provided on the confronting sides of said plates and being circularly arranged, a series of spaced arcuate baffles provided on the other side of the plate having the inlet opening therein which are arranged in spaced overlapping relation with respect to the series of baffles on the casing part, whereby to divide the volume of gases and impart an initial cooling of the gases entering the casing and for causing the incoming gases to be whirled toward the peripheries of the plates, and a series of spiral baffles provided on the other side of the plate having the diverting cone which are disposed in spaced overlapping relation to the spiral baffles on the casing part for whirling the initially cooled gases to the outlet and for effecting a further cooling thereof.

3. A vacuum type muffler comprising in combination, an annular casing composed of two shell like casing sections, fastening bolts passing through said casing sections, a concentric inlet in one end wall of said casing, an outlet in the opposed end wall of said casing, a pair of annular plates having notches in their peripheries through which said bolts pass, the peripheries of said plates being disposed in spaced relation to the annular wall of said casing, means for maintaining said plates in spaced relation and in fixed spaced relation to the side walls of said casing to divide the interior of the casing into a pair of gas inlet chambers and a single gas outlet chamber, the plate nearest the inlet having a gas inlet opening in axial alignment with said inlet but being of a smaller diameter, spaced overlapping arcuate baffles arranged in circular formation on the confronting side walls of the inlet chambers to cause a whirling of the hot gases as they pass through the inlet chambers and for initially cooling the same, and spaced spiral overlapping baffles provided on the confronting walls of the outlet chamber, the inner ends of the spiral baffles terminating at said outlet whereby the initially cooled gases are further cooled and whirled as they pass about the spiral baffles for subsequent exhaust to the atmosphere through said outlet.

4. A vacuum type muffler as set forth in claim 3, in which that plate forming one side wall of the outlet chamber is provided on one side with a stream diverting cone which extends toward the inlet opening in the other plate, and a hub portion provided on the other side of said plate extending toward the outlet and being of a smaller diameter than the outlet and concentric therewith and cooperating with the walls of the outlet to provide a restricted annular passage between the outlet chamber and the outlet.

CHARLES L. HILL.
